UNITED STATES PATENT OFFICE.

HANS ANDERSON, OF OAKLAND, CALIFORNIA.

SINGLE-BLADE PLANE.

1,414,974.

Specification of Letters Patent. Patented May 2, 1922.

Application filed November 22, 1921. Serial No. 517,074.

To all whom it may concern:

Be it known that I, HANS ANDERSON, a citizen of the United States, and a resident of Oakland, county of Alameda and State 5 of California, have invented a new and useful Single-Blade Plane, of which the following is a specification.

The present invention relates to improvements in single blade planes and its particular object is to provide a plane that is capable of very fine adjustment, comparatively simple in construction and that is so constructed and holds the blade in such a manner that it can be used as a block 10 plane as well as a smoothing plane.

With these objects in view I have illustrated the preferred form of my invention in the accompanying drawing, in which Figure 1 shows a longitudinal cross section 20 through my plane; Figure 2 a top plan of the same; Figure 3 a top plan view of a blade supporting block used in connection with my plane; Figure 4 an end elevation of said block; Figure 5 a side elevation of 25 the same; Figure 6 a longitudinal cross section through a guiding member used in my device, and Figure 7 an end view of the same.

While I have illustrated one preferred 30 form of my invention only, it will be understood that slight changes or modifications within the scope of the claims may be made without departing from the spirit of the invention.

My plane (1) comprises the bottom plate (2) flanked by two flanges (3) and provided with a transverse slot (4) through which the cutting edge (6) of the blade (7) extends. The blade rests on an inclined 35 plane (8) forming the upper face of a block (9) shown in detail in Figures 3, 4 and 5. The block is secured to the plate in operative proximity to the slot by means of screws extending through slots (11) in the block 40 and secured to rectangular projections (10) rising from the bottom plate (2). The slots (11) allow of limited longitudinal adjustment of the block relative to the bottom plate. A central rear portion of the block 45 is cut away to form the recess (12) adapted to receive the guiding member (13) which rests on the seats (14) provided within the recess in parallel relation to the inclined plane of the block. The two seats are joined 50 at the rear end by a connecting member (16) so that a rectangular hole (17) is formed

between the seats and the end member (16) adapted to receive a downward projection (18) extending from the guiding member (13). The end member (16) is provided 60 with a perforation (19) adapted to receive the screw (21) which is held against longitudinal motion by the two collars (22), the threaded end of which engages a corresponding threaded recess in the projection 65 (18) of the guiding member (13) so that the guiding member may be moved in either direction by means of the screw (21), which is provided with a milled head (23) to facilitate its handling.

It will be noticed from the drawing that the screw (21) is supported in parallel relation to the seat as well as the inclined plane of the block. The blade (7) is provided on its under surface with a plurality 75 of grooves (24), each of which is adapted to engage a small projection (26) rising from the upper surface of the guiding member (13) so that the blade is forced to follow the motions of the guiding member. 80 The blade is further provided with a slot (29) through which extends the screw (31) binding the wedge (32) to the inclined plane of the block (9). The wedge is provided with a circular perforation (33) connecting with a slot (34) which extends from the circle into a heavier portion of the wedge so that when the wedge is placed on the 85 blade with its circular perforation surrounding the screw (31) and is then forced downward along the inclined plane, the slot (34) will engage the head of the screw (31), and due to its wedging action, will force the blade into firm contact with the inclined plane.

To intensify the contact and to concentrate its intensity on the forward or cutting edge of the blade, I provide a screw (36) in the upper end of the wedge adapted to be screwed through the same and to press 100 against an adjacent portion of the blade, whereby the upper end of the wedge is forced away from the blade and the pressure of the lower end of the wedge against the blade intensified.

It will be seen from this description that the construction of my plane offers many advantages relative to its adjustability and the openness of its structure. It offers three distinct means for adjustment comprising 110 the longitudinal adjustment of the blade supporting block (9), the adjustment of the

blade on the same by means of the guiding member (13) and the adjustment of the pressure brought to bear on the front end of the blade by means of the screw (36).
5 A handle (37) is secured to the plane in the usual manner and a means for guiding the front end of the plane is provided in the transverse member (38).

I claim:

- 10 1. In a single blade plane, means for adjustably supporting the blade in an inclined position, comprising a block having a slanting blade engaging surface, a recess in the rear end of the block having a slanting bottom parallel to the block surface with a central hole, a guiding member operatively engaging the undersurface of the blade adapted to ride on the recess bottom having a downward projection extending through the hole, and means supported in the rear wall of the block threadedly engaging the
- 15
- 20

downward projection for adjusting the position of the guiding member.

2. In a single blade plane, means for adjustably supporting the blade in an inclined 25 position, comprising a block having a slanting blade engaging surface, a recess in the rear end of the block having a slanting bottom parallel to the block surface with a central hole, a guiding member operatively 30 engaging the undersurface of the blade adapted to ride on the recess bottom having a downward projection extending through the hole, and means supported in the rear wall of the block threadedly engaging the 35 downward projection for adjusting the position of the guiding member, said means comprising a screw having a milled head and two shoulders engaging opposite sides of the rear wall for holding the same against 40 longitudinal motion.

HANS ANDERSON.
